UNITED STATES PATENT OFFICE

ALAN H. LEAMY, OF AUBURN, INDIANA, ASSIGNOR TO AUBURN AUTOMOBILE COMPANY, OF AUBURN, INDIANA, A CORPORATION OF INDIANA

DESIGN FOR AN AUTOMOBILE

Application filed April 24, 1931. Serial No. 39,614. Term of patent 7 years.

To all whom it may concern:

Be it known that I, ALAN H. LEAMY, a citizen of the United States, and a resident of Auburn, county of De Kalb, and State of Indiana, have invented a new, original, and ornamental Design for an Automobile, of which the following is a specification, reference being had to the accompanying drawings, forming a part thereof.

Fig. 1 is a view in top plan elevation of the automobile showing my new design.

Fig. 2 is a view in side elevation thereof.
Fig. 3 is a view in rear elevation thereof, and

Fig. 4 is a view in front elevation thereof.
I claim:—

The ornamental design for an automobile substantially as shown.

ALAN H. LEAMY.
